DRAW OVEN

Clifford B. Ferree, Pittsburgh, Pa.

Application November 18, 1936, Serial No. 111,408

2 Claims. (Cl. 266—5)

This invention relates to the production of forged steel rolls, and consists in a method of procedure, and an apparatus, whereby the possibility is realized of tempering a forged roll by "air drawing," with benefits and advantages to be described. This application is a continuation in part of an application for Letters Patent filed by me August 28, 1935, Serial No. 38,195.

In the production of forged-steel rolls, after a roll has been machined and hardened and before polishing for delivery to the user, it is subjected to an ultimate tempering step. This ultimate tempering step, commonly called "drawing" (in that extreme hardness is in some degree reduced or drawn from the metal), consists in raising the roll from atmospheric temperature to a temperature that in different cases may range from as low as 290° F. to as much as 425°, or, in extreme cases, even to 700 or 800°, and cooling it again in the open air. This heating of the roll is a very nice operation: it must be accomplished in very uniform manner, that the quality of the finished roll shall be uniform throughout all its extent. Heretofore this ultimate heating has been performed in a bath of oil. Alternative methods of tempering, practised upon other bodies intended for other uses involve, one, the employment of a bath of molten lead, and, another, heating in the gaseous atmosphere of an oven; these two other methods are characterized "lead drawing" and "air drawing." The latter term is inaccurate, in that the atmosphere is not atmospheric air, but rather a gaseous furnace atmosphere; but the term has gained acceptance, and is understood. I shall use it in accepted manner and my use of it will not be misunderstood. Lead drawing is not appropriate to the ultimate tempering step in the production of a forged roll, because the melting-point of lead is beyond the temperature range that is requisite; air drawing has not hitherto been made practical, because of the wide disparity in thermal capacity per unit of volume between steel and "air" (i. e., furnace atmosphere) and because of the great mass of a roll body, in relation to surface area.

I have discovered that by providing an oven so constructed that the gas burning within shall build up a super-atmospheric pressure in the oven chamber, by forming the furnace walls of material of low heat conductivity, and by burning within the chamber a gas of high heat value mingled with air in relative quantities such as to effect perfect combustion, I am able for the first time to overcome the difficulties and for the first

time successfully and advantageously to "draw" a forged roll in "air."

In the accompanying drawings Fig. I is a view in plan from above of an oven of the invention, actually built and used industrially, from which the roof has been removed; Fig. II is a view of the same unroofed oven in side elevation; and Fig. III is a view of it in vertical and transverse section, with the roof in place. And in Fig. III a roll is shown in end elevation, in place within the oven. Fig. IV is a chart showing comparatively the heat losses of the apparatus of my invention and those of a tank for oil-drawing.

The oven is essentially an oblong chamber of approximately square cross-section, and of such particular dimensions as to receive the rolls to be treated. The chamber within is, but for a partition wall that affords longitudinal subdivision, free of any screen: there is no baffle nor flame-diverting nor flame-confining partition between the burner and the article under treatment. The flame has free access to the naked roll surface. Such a chamber I characterize a free chamber. In ordinary circumstances a plant will be required to produce rolls of various dimensions, and the oven will be of sufficient size to receive the largest. In this instance the oven measures, internally, 16 feet 11 inches in length, 5 feet in breadth, and 5 feet in height. There are within the oven chamber guides that define a space that is 3 feet 9 inches wide; so that this oven is adapted to receive any roll not substantially exceeding 16 feet in length nor 3 feet 6 inches in maximum diameter. I have successfully treated in this oven, having the characteristics herein described, and by following the procedure herein set forth, rolls that ranged in size from 28x55 inches downward. The size given is not a limitation; it happens merely to be the size of the largest rolls I have hitherto had occasion to produce. I have found it advantageous to provide a removable partition or curtain wall, subdividing the oven chamber, to the end that for relatively short rolls a portion only of the oven structure need be used; and I have found it convenient thus to reduce the size of the oven by half. Rolls of the maximum size indicated have volume approximately one fourth that of the furnace chamber.

The side walls 1 and the end walls 2 are continuous and unbroken and stand permanently fixed upon the floor 3. The roof 4 is preferably made in sections longitudinally of the oven; and it, as has been said, is removable. It rests when in place upon the side and end walls; and it too is substantially continuous. The oven

throughout lacks port or chimney. No other exit for gases is found or provided than the inevitable and small spaces and seams that are incident to a removable roof construction. Such small spaces are desired, and no provision is made for sealing them. The floor is conveniently of concrete; the side walls and roof are formed of heat-insulating material properly supported. The effective material for this purpose, because 10 of its high insulating value and its low capacity to absorb heat, is the porous brick that is produced by mixing a refractory preparation with sawdust or the like, molding the mass, and firing. The brick so produced is porous and light in weight, and possesses the other characteristics named. A material of this nature adequate for the purpose is known on the market by the trade-name Nonpareil. The side-walls of my oven, formed of this material, are 4½ inches thick. 15 The roof of the same material is 5½ inches thick. The walls are secured and reenforced by externally arranged vertically standing posts 5 set in the concrete base, and by the marginal angles 6. The bricks that form the roof are clamped between channels 7 by means of through-bolts 8 and the clamping means are cushioned by springs 9. The bricks of the roof are, as indicated in Fig. III, assembled to the form of a low arch; and to the structural characteristic of 20 an arch the individual bricks may be minutely shaped. The roof bricks are further shaped in detail with recesses, to permit the passage of the clamping bolts. It will be noted that the maximum interior height of the oven (5 feet) is attained at the peak of the roof arch. The walls stand slightly lower (4 feet 10 inches).

At a suitable point or points in the extent of the side walls 1 opposite vertically extending channels 10 are set, to serve as guides and supports for the partition wall 11 that, when the roof is off, may be removably introduced from above. This partition wall is preferably made of the same porous brick that has been mentioned, carried in a suitable frame. For application and removal the partition is provided with 25 lifting rings 12.

Standing within the oven chamber are guides that limit the position of a roll within the chamber and prevent any striking of the relatively fragile walls by a swinging of the heavy roll when being manipulated in introduction into and removal from the oven. These guides are here shown as lengths 13 of rail, embedded at their bases in the concrete floor and standing vertically in alignment within the side walls. They are conveniently arranged in opposite pairs and stand, as has been noted, at a spacing of 3 feet 9 inches apart.

Along the floor longitudinally extends a pair of rails 14, upon which two wheeled bogies 15 may run. Upon these bogies stand Y-blocks 16 to afford rests for the necks at the two ends of a roll, and thus an introduced roll is supported and carried during the course of treatment. The bogies run on the tracks to afford adjustment to variation in roll length and to define the position of the roll with respect to the length of the oven.

At the floor within the chamber, and along the bases of the side walls, extend gas headers—one or, conveniently, two on each side, 17 and 18. These headers are provided each with a succession of horizontally and inwardly directed nozzles 19, and through feed-pipes 20 gaseous fuel of high heat value (natural gas, for example) is

supplied and maintained at suitable pressure within the headers. If, as is convenient, two so-constituted burners be provided on each side, one (preferably the lower) may serve as a heating-up burner; the other as a holding burner. 5 The nozzles of the heating-up burners will in any case be horizontally and inwardly directed; some of the nozzles of the holding burners (preferably not all, nor more than half of them) may be directed vertically upward. It will be understood that the supplies of fuel to the burners severally are controlled by valves, so that the burners of the two designations may serve severally or jointly. The headers are formed of two-inch pipe, the nozzles of half-inch pipe. The 10 nozzles of each of the heating-up burners are here shown to be twelve in number, evenly spaced throughout the length of the oven; and, as between the opposite heating-up burners, the nozzles are staggered, so that the line of direction 15 of each lies between the lines of two nozzles on the opposite side. The number of nozzles upon the holding burners is less. Six for each burner are here shown; and, in their spacing, the nozzles of the two holding burners are staggered and 20 their lines of direction lie in spaces between lines of direction of the nozzles of the heating-up burners.

I have given the actual dimensions of a particular installation; it will be understood that these 30 figures are given by way of illustration, and are not intended to be taken as a limitation upon the invention; since, manifestly, these dimensions may be varied.

The burners are supplied with a perfectly combustible gaseous mixture at a pressure such that in operation blue flames are projected from the nozzles of about 2-3 inches in length, and combustion is complete.

It will be understood that, the oven being 40 equipped with such a removable partition as 11, the burner arrangement may be made in two units, one on each side of the partition, and the units may be severally operable in the manner described, so that the fractional parts of the oven 45 may be severally operated.

In operation, a roll to be treated is introduced into the unroofed oven and is lowered to rest by its necks upon the Y-blocks of the two bogies suitably adjusted in position within. The roof is then applied, and the heating-up burners are lighted. The valves are suitably adjusted and gradually the oven and its charge are brought to peak temperature.

Referring to Fig. III the roll R will be seen in 55 position upon the bogies, its face standing free, and enveloped throughout all its extent in the atmosphere within the oven. The oppositely placed heating-up burners 17 may be understood to be projecting their flames horizontally, in a 60 plane somewhat below but not widely spaced from the horizontal plane that is tangent to the lower limb of the curvature of the face of the roll. There is no deflecting baffle nor confining partition; the flames spurt horizontally across 65 the free space between the roll and the furnace floor. This condition of the roll with respect to the flame I define in characterizing the roll when in position as "naked." Remembering that the nozzles of the opposite burners succeed one another in staggered succession throughout the 70 length of the oven, it will be perceived that the flames tend to set up a succession of oppositely directed swirls of hot gases around the roll body. Remembering that the closed oven is (but for the 75

seams in the roof) tight walled, it will be perceived that the play of the flames tends to build up pressure within the oven chamber and to exclude atmospheric air. The practical and actual effect is that an inert atmosphere of high temperature is maintained within the oven; that the actual temperature may by the adjustment of the supply valves be varied and brought to the desired degree; and that within all the oven chamber from floor to roof the temperature may be maintained uniform, within a permissible tolerance of ten degrees F.

If natural gas be used, the oven atmosphere will, with inconsiderable variation, be carbon dioxide, 10%; water vapor, 18%; nitrogen, 72%. If fuel gas be used, while the components of the oven atmosphere will be the same, the proportions will be somewhat different.

When in continued operation the roll within the oven has come to furnace temperature, the heating-up burners may be shut off, and the holding burners only continued in action. In case the nozzles of the holding burners are all horizontally placed, the holding burners may have been cooperating with the heating-up burners in their essential function; but in case some of the nozzles of the holding burners are vertically directed, the holding burners will be brought into service in alternation with the heating-up burners.

When the roll has been held at peak temperature the desired length of time (typically fourteen hours), the burners are shut off, the oven is opened, and the roll removed. While the roll may be brought into the open air at any preferred point in the course of its cooling, it ordinarily will be removed without delay, when the heat treatment is completed. The emptied oven will cool rapidly and will without long delay be available for operation upon another roll.

I have found that at a peak temperature of 350° F., that is to say, with a temperature difference on opposite sides of the wall of 250° or somewhat more, the heat loss in my oven is 55,000 B. t. u. per hour. The heat loss in a tank of comparable size for oil-drawing is 220,000 B. t. u. per hour. A comparative showing of heat loss in the apparatus of the two types throughout the range of ordinary operation is given in the chart, Fig. IV.

The heat generation in my oven to effect what is termed a "low" draw (the usual procedure) is at a rate that ranges from 45,000 B. t. u. per hour to 226,000, and the average is approximately 80,000 B. t. u. per hour. The saving in heat expenditure over the heretofore prevailing oil-drawing practice is about seventy per cent. For high draw in the practice of my invention the heat generation ranges from 45,000 B. t. u. per hour to 457,000. It then will be manifest that in normal operation the heat penetrability of the walls of my furnace is less than 200 B. t. u. per square foot per hour, and that the heat generation within the chamber exceeds 200 B. t. u. per square foot per hour and very considerably exceeds the rate of loss through wall permeability.

The control of temperature is more accurate in the practice of my invention than is possible in the oil-drawing procedure. By actual observation it is found that the variation in peak temperature in the practice of my invention averages 12 degrees F., whereas in the oil-drawing procedure the variation amounts to 22 degrees.

When, as ordinarily will be the case, the roll is removed from the oven immediately on the

completion of the heat treatment, the empty oven will in the course of one or two hours have cooled sufficiently to allow it to receive another roll for treatment. No such speed of operation is attainable in the oil-drawing procedure.

It is desirable, in order to gain toughness, that a relatively high peak temperature be attained; but a relatively high peak temperature is, in the oil-drawing procedure, gained only with loss of hardness. Actual experience shows that it is possible in my "air-drawing" procedure to attain higher peak temperatures than in the old oil-drawing procedure while maintaining a like degree of hardness.

The oil-drawing procedure is limited, in the matter of peak temperature, by the necessity of operating below the flash-point of the oil. No such limitation attends my "air-drawing" procedure.

There are serious disadvantages attendant upon the oil-drawing procedure, from which the "air-drawing" procedure of my invention is free. The first and most serious of these is the fire hazard. Operation is in any case and of necessity dangerously near the flash-point of the oil; and because there is variability here that cannot be wholly eliminated, accidents occur, with injury to men and property. It happens inevitably that a roll often carries water to the oil tank, and when this occurs the fire hazard is increased.

The roll as it comes from the oil bath in the oil-drawing operation is coated with oil, and the oil coating delays its cooling to room temperature—and cooling to room temperature is necessary, before work upon the roll can be resumed. Furthermore, when at length the roll comes to the grinding wheel, the heavy coating of oil upon its surface clogs the wheel, and necessitates wheel dressing. From all such embarrassments procedure under my invention is free.

I believe myself to be the first successfully to draw a rolling-mill roll in "air".

I claim as my invention:

1. A draw oven for the heat treatment of a rolling-mill roll, including floor, side walls, and roof, the side walls and roof being formed of heat-insulating material of low heat-absorption capacity, the roof being removable and the seams incident to the removable-roof construction affording the sole exit for gas from the chamber within the closed oven, means for supporting by its necks within the chamber and with its face free and enveloped throughout all its extent in the atmosphere within the oven a roll to be treated, and means for projecting into the otherwise free chamber from opposite sides and in a horizontal plane below the lower limb of curvature of a roll supported within the oven chamber two lines of flame.

2. A draw oven for the heat treatment of a rolling-mill roll, including floor, side walls, and roof, the side walls and roof being formed of heat-insulating material of low heat-absorption capacity, the roof being removable and the seams incident to the removable-roof construction affording the sole exit for gas from the chamber within the closed oven, means for supporting by its necks within the chamber and with its face free and enveloped throughout all its extent by the atmosphere within the oven a roll to be treated, and means for developing in the otherwise free chamber in a horizontal plane below the lower limb of curvature of a supported roll an outspread substantially uniform layer of flames.
